UNITED STATES PATENT OFFICE.

MARIUS LATOUR, OF PARIS, FRANCE.

, RADIORECEIVER.

Application filed July 14, 1920. Serial No. 396,281.

(GRANTED UNDER THE PROVISIONS OF THE ACT OF MARCH 3, 1921, 41 STAT. L., 1313.)

To all whom it may concern:

Be it known that I, MARIUS LATOUR, citizen of the Republic of France, residing at Paris, in the Republic of France, have 5 invented certain new and useful Improvements in Radioreceivers, (for which I have filed applications as follows: French Patent No. 503,047, filed October 21, 1916; Great Britain application No. 20,809, filed July 10, 1920), of which the following is a specification.

This invention relates to a receiving arrangement for the reception of electromagnetic waves.

15 According to the present invention such waves from a remote signalling source control the condition of a thermionic filament.

The invention is more particularly described with reference to the accompanying 20 diagrammatic drawings—

Figure 1 represents the arrangement of the system when a battery is used as a local source for the lamp.

Fig. 2 is a diagram of the lamp circuit 25 when a generator is used for this purpose.

The receiving aerial 1 acts on a circuit 2 comprising an inductance and a capacity which feeds a high frequency amplifier. This amplifier is formed by several thermionic elements with three electrodes, grid G, anode P, and filament F, mounted in usual manner. The filaments of these thermionic elements are heated by a source of 30 electrical energy 3 whilst their anodes are raised to the necessary potential by a source of electrical energy 4.

The filament-anode circuit of the last 40 amplifying tube acts through a transformer 6 on a small lamp 7, having as fine a metallic filament as possible (for instance of tungsten). Each wave received by the aerial and amplifier directly raises the filament to incandescence.

By the aid of the luminous incandescence 45 of the filament an impression may be taken on a photographic band which is automatically unwound before a window illuminated by the said filament.

In view of the dimensions of the filament, 50 calorific inertia is extremely small and consequently extremely rapid wave emissions

may be received which are sent out by a transmitter automatically operated.

The sensitiveness of the arrangement may be increased by previously heating the filament by a source of current 8, which by its action brings the filament to a temperature just under that at which it emits photographic radiations. Under these conditions the waves received will only have to furnish 55 supplementary energy to cause the filament to make an impression on the photographic band.

By this arrangement continuous waves 60 may be received without any special heterodyne device. Nevertheless a small local generator of continuous waves of the same frequency as that of the sending station may be substituted for the source of direct current 8, in such a way that the energy 65 of the waves emitted by the local generator is added to that of the waves received.

Although the arrangement just described 70 allows of waves being received without using a detector, it is also evident that the amplifier might be placed subsequently to a detector of any kind and thus make the amplification of low frequency.

Another modification consists in rectifying 75 the current before its admission to the thermionic tube. This rectifying may be done with the aid of valves or detectors placed subsequent to the amplifying system. An advantage may be obtained from such detection with regard to sensitiveness if the 80 source of current 8 be retained.

The shunt resistance 9 will be preferably placed across the terminals of the lamp to 85 protect the latter against too violent stray currents by acting as a voltage limiter.

Although the invention has been described 90 assuming that an incandescent lamp is employed the arrangement extends to the case where any other luminous source is employed, the brilliancy of which may be regulated by an electrical potential or current.

If the system be applied to a receiver for 95 wireless telephony, a photographic strip similar to a recording photographic cylinder is obtained. By causing this photographic strip to pass like a cinematograph film before a selenium cell inserted in a cir-

cuit comprising a battery and a telephone, the said telephone is able to reproduce the conversation received.

I declare that what I claim is:—

- 5 1. A receiver for high frequency signals and the like comprising a thermionic tube amplifier, an incandescent lamp connected with the said amplifier to be fed thereby, and an additional feeding source connected 10 to said lamp to bring it to incipient incandescence.
- 15 2. A receiver for high frequency signals and the like, comprising a thermionic tube amplifier, an incandescent lamp connected with the said amplifier to be fed thereby, and a local generator producing waves in synchronism with the incoming high frequency signals, said generator raising said lamp to incipient incandescence.
- 20 3. A receiver for high frequency signals and the like, comprising in combination a thermionic tube amplifier, an electric lamp connected to the said amplifier and fed

thereby and an additional feeding source connected to the said lamp, said additional 25 feeding source being formed by a local generator of continuous oscillations.

4. The method of rendering imperceptible high frequency signals and the like perceptible, which comprises converting such 30 signals into electric currents, and passing such currents through a resistance independently maintained near a temperature of incandescence.

5. The method of converting imperceptible high frequency signals and the like into perceptible manifestations which comprises converting said signals into electric currents, combining said currents with currents from an independent source, and passing such combined currents through a resistance adapted to be brought to a state of 35 incandescence thereby.

In witness whereof, I have hereunto signed my name.

MARIUS LATOUR
